UNITED STATES PATENT OFFICE.

SAMUEL KAHAN AND ALBERT WILLIAM CRAVEN, OF MELBOURNE, VICTORIA.

ELECTRIC ALARM-CLOCK.

SPECIFICATION forming part of Letters Patent No. 398,896, dated March 5, 1889.

Application filed October 13, 1888. Serial No. 287,983. (No model.)

To all whom it may concern:

Be it known that we, SAMUEL KAHAN, watch-maker, and ALBERT WILLIAM CRAVEN, civil engineer, subjects of the Queen of Great Britain, residing, respectively, at Clerkenwell House, Burwood Road, Hawthorn, near Melbourne, in the British Colony of Victoria, and at 123 Collins Street, West Melbourne, aforesaid, have invented new and useful Improvements in Electrical Alarm-Clocks, of which the following is a specification.

This invention of improvements in electrical alarm-clocks has been designed for the purpose of obviating certain objectionable features which have been incidental to electrical alarm-clocks as heretofore constructed. The means hitherto employed for utilizing the movement of certain parts of a clock for completing an electrical circuit through a bell have usually consisted of some form of contact-piece arranged to be shifted around the dial of the clock and to make contact with the hour-hand at certain times, according to its position on the dial. We have found in practice, however, that by reason of the slow movement of the hour-hand the contact between it and the contact-piece continued for a longer period than was desirable, thus causing either a very appreciable waste of the electrical energy of the battery or else necessitating the breaking of the bell-circuit by means of a switch or the like—a practice that is open to many obvious objections.

By our invention we are enabled to limit the duration of time during which the electrical circuit is complete through the bell. Instead of making contact through the hour-hand of a clock, we utilize the motion of the arbor of one of its quick-moving wheels by securing thereon a ratchet-wheel, which is caused to engage with a pawl on a spring rock-shaft or arbor, when a pin projecting from the front of a longitudinally-sliding sleeve enters a notch in the face of a cam-wheel, thereby allowing a flat steel spring to move the spring rock-shaft longitudinally, and so cause its pawl to engage with the ratchet-wheel, so that a rotary motion will be imparted to the said rock-shaft, which will cause a contact-piece on its end to complete an electrical circuit through the bell. If preferred,

our invention may be arranged to be worked on a "close" circuit by causing the contact-piece on the rock-shaft to break an electrical circuit, so as to operate a relay, which will thus complete the bell-circuit. We provide the clock with a suitable switch, whereby it may be cut out of the electrical circuit in order to render the alarm inoperative.

Having now generally described and ascertained the nature of our invention and in what manner the same is to be performed, we will proceed to describe the same more particularly with the aid of the accompanying drawings, in which—

Figure 1 is a rear elevation of the works of an electrical alarm-clock embodying our invention. Fig. 2 is a plan. Fig. 3 is a front elevation with part of the face of the clock broken away; and Fig. 4 is a side elevation of the same.

A represents the ratchet-wheel, which is secured upon the arbor *a* of one of the quick-moving wheels of the clock, and *B* is the balanced pawl, which is pivoted between two arms, *b b*, projecting from the rock-shaft *C*, whose outer end carries a contact-piece, *D*, arranged to complete an electrical circuit through a bell by contacting with the insulated spring *D'*. The contact-piece *D'* is held normally out of engagement by a spring, *C'*, as shown in Fig. 1.

c represents the coil-spring, which always tends to hold pawl *B* out of engagement with ratchet-wheel *A* by keeping the rock-shaft *C* in the position indicated by dotted lines in Fig. 2.

E represents the face cam-wheel, which is formed on a sleeve fitting loosely over the arbor of the hour-hand wheel, and is provided with a hand, *e*, Fig. 2, whereby it can be turned into such a position that the pin *e'* will enter the notch *e*² in the cam-wheel *E* at the moment the hour-hand points to the time the alarm is set for.

F represents the spring which causes the rock-shaft *C* to move longitudinally when the pin *e'* enters the notch *e*² against the resistance of the spring *c*, thus causing the pawl *B* to engage with the ratchet-wheel *A*, which then pushes back the arms *b b*, and so partially rotates the rock-shaft *C*, so causing the piece

D to contact with insulated spring D', thus completing the circuit through the bell. As the ratchet-wheel A continues to rotate, it will cause the pawl B to turn over into the 5 position indicated by dotted lines in Fig. 1, thus allowing the rock-shaft C and contact-piece D to again return to their normal positions.

It is evident that the period of contact between the piece D and the spring D' may readily be regulated by adjusting the said spring by means of the set-screw d'. If it is set nearer to the contact-piece D, then the bell will ring for a longer period—say from five 15 seconds upward—and, vice versa, if the spring is set farther away, the duration of the contact, and therefore the ringing of the bell, will be shortened.

Having now particularly described and ascertained the nature of our invention and in what manner the same is to be performed, we declare that what we claim as our improvements in electrical alarm-clocks is—

1. In an alarm-clock, the combination, with 25 a make-and-break device interposed in an alarm-circuit and one of the quick-going arbors of the going train, of a shifting mechanism controlled by a slow-going arbor of the going train and connecting devices controlled 30 by the shifting mechanism for connecting the make-and-break device with the quick-going arbor, substantially as and for the purposes specified.

2. In an alarm-clock, the combination, with 35 a make-and-break device interposed in an alarm-circuit, one of the quick-going arbors of the going train, and a connection between one element of the make-and-break device and the quick-going arbor of the going train, consisting of a longitudinally-movable rock-shaft 40 on which such element is mounted, a pawl secured to said rock-shaft, and a ratchet-wheel on the quick-moving arbor, of a shifting mechanism controlled by a slow-going arbor of the

going train and adapted to operate on the 45 rock-shaft to move the pawl into and out of engagement with the ratchet, substantially as and for the purposes specified.

3. In an alarm-clock, the combination, with 50 one of the quick-going arbors of the going train, a make-and-break device, and a ratchet-and-pawl connection between the two, of shifting mechanism adapted to move the pawl into and out of engagement with the ratchet and a controlling device operated by a slow-going 55 arbor of the going train, consisting of a cam, and a connection between the cam and pawl-shifting mechanism, substantially as and for the purposes specified.

4. In an alarm-clock, the combination, with 60 a quick-going arbor of a clock-going train, a ratchet-wheel, A, secured thereto, the hour-hand arbor of said train, and the cam E mounted thereon, of the contact D, a longitudinally-movable rock-shaft for said contact, 65 a pawl carried on the rock-shaft and adapted to engage the ratchet on the quick-going arbor, and a shifting device connected with the rock-shaft and controlled by the cam on the hour-hand arbor to move the pawl into and 70 out of engagement with the ratchet, substantially as and for the purposes specified.

5. In an alarm-clock, the combination, with 75 a quick-going arbor of a clock-going train, a ratchet-wheel, A, secured thereto, a longitudinally-movable rock-shaft, C, the pawl B, and spring c mounted thereon, of the hour-hand arbor, the cam E loose thereon and provided with a hand, e, the sliding pin e', and the spring F, said parts being arranged and 80 operating substantially as and for the purposes specified.

SAMUEL KAHAN.

ALBERT WILLIAM CRAVEN.
